UNITED STATES PATENT OFFICE

125,037

DESIGN FOR A SCAFFOLDING UNIT

Charles C. Pimm, West Somerville, Mass.

Application August 19, 1940, Serial No. 94,504

Term of patent 14 years

To all whom it may concern:

Be it known that I, Charles C. Pimm, a citizen of the United States, residing at West Somerville, in the county of Middlesex and State of Massachusetts, have invented a new, original, and ornamental Design for Scaffolding Units, of which the following is a specification, reference being had to the accompanying drawing, forming part thereof.

In the drawing, which illustrates the new ornamental design:

Figure 1 is an elevation of a scaffolding unit

showing my new design which is the same on the opposite side thereof;

Figure 2 is an end elevation of the scaffolding unit shown in Figure 1 and showing my new design; and

Figure 3 is a plan view of the scaffolding unit shown in Figures 1 and 2 and showing my new design.

I claim:

The ornamental design for a scaffolding unit, as shown and described.

CHARLES C. PIMM.
